(57) **CLAIM**

The ornamental design for a combination tube and headset of a stethoscope, as shown and described.

DESCRIPTION

FIG. 1 is a top plan view of a combination tube and headset of a stethoscope showing my new design, in an environment; FIG. 2 is a bottom plan view thereof;

FIG. 3 is a top plan view of the combination tube and headset of a stethoscope showing my new design removed from the environment for ease of illustration;

FIG. 4 is a bottom plan view thereof;

FIG. 5 is a right-side elevation view thereof;

FIG. 6 is a left-side elevation view thereof;

FIG. 7 is a front end view thereof;

FIG. 8 is a rear end view thereof; and,

FIG. 9 is a perspective view thereof.

The broken lines shown in the views are included for the purpose of illustrating portions of the combination tube and headset of a stethoscope that form no part of the claimed design.
